MARTIN ROECKNER, OF MULHEIM-RUHR, GERMANY, ASSIGNOR TO THE FIRM OF VEREINIGTE STAHLWERKE AKTIENGESELLSCHAFT, OF DUSSELDORF, GERMANY

METHOD OF ROLLING TUBES FROM HOLLOW BLOCKS

Application filed February 6, 1928, Serial No. 252,376, and in Germany February 25, 1927.

It is known, for instance by my prior U. S. Patent 1,610,593, to make tubes from a hollow block by subjecting the latter to the action of a system of pairs of rolls arranged about the hollow block at a certain distance from its axis, each pair of rolls acting with one roll from inside and with the other roll from outside said block upon the walls of the latter. The pairs of rolls are of gradually increasing width and of adjustable working depth so that from the first pair of rolls a circumferential nick beginning adjacent the front end of the block is cut into the material of the hollow block, which nick is gradually widened by the following pairs of rolls toward said end; the axes of said rolls being inclined to the axis of the hollow block.

Said method has the drawback that slight corrugations and unevenesses in the wall of the tube produced, which sometimes occur by action of the working part of the rolls thereon, could hitherto not be removed by a working process directly adjoining the rolling process. It was necessary, for a removal of said slight corrugations and unevenesses, to use a separate machine, for instance one used for rounding and straightening welded tubes.

The present invention provides improved means for overcoming this drawback and permitting to remove said slight corrugations and unevenesses of the tube directly after its formation without the use of a separate machine. To this end, according to the invention, the rolls are beyond their working part at their outlet end provided with an extension, of which the diameter and formation is so determined that the diameter of the tube, directly after the formation of the latter, is widened and that the rolled and widened part of the tube receives a pressure from said roll extensions without its being further deformed.

The accompanying drawing illustrates how the invention can be put into practice.

Figs. 1 and 2 illustrate the improved arrangement for putting the invention into practice.

The reference letters designate: A the main deforming part of the rolls, B the hollow

block to be rolled, C the outlet extension widening the rolled tube, and D that part imparting a pressure to the tube without deforming the same.

What I claim, is:

In a method of rolling tubes from hollow blocks consisting in drawing out the latter in substantially axial direction by the utilization of pairs of rolls acting both from inside and outside upon said block and of which the axes are inclined to the axis of the latter, widening the tube by the same pairs of rolls directly after its formation from the hollow block and subsequently imparting thereto a pressure without deforming it by outlet extensions of said rolls.

In testimony whereof I have hereunto set my hand.

MARTIN ROECKNER.
